REFRIGERATOR

Sigurd Mattias Bäckström, Stockholm, Sweden,
assignor, by mesne assignments, to Servel, Inc.,
New York, N. Y., a corporation of Delaware

Application September 6, 1935, Serial No. 39,373
In Germany October 5, 1934

12 Claims. (Cl. 62—89)

My invention relates to refrigerators and has for an object the provision of an improved refrigerator structure which is sturdy yet readily assembled and inexpensive.

5 Another object is to provide improved distribution of the weight of a refrigerating apparatus in a cabinet.

My invention together with the objects and advantages thereof will fully appear upon consideration of the following description in conjunction with the accompanying drawings forming part of this specification, and of which:

Fig. 1 is a perspective view of a refrigerator cabinet embodying the invention;

15 Fig. 2 is a vertical section of the refrigerator; Fig. 3 is a horizontal section taken on line 3—3 in Fig. 2; and

Fig. 4 is a rear view of the refrigerator.

Referring to Fig. 1, a refrigerator cabinet 10 20 provides a thermally insulated storage compartment 11 accessible by means of a door 12. The cabinet includes a front frame 13 constructed of upright corner posts 14 and 15 joined in a suitable manner by cross members 16 and 17. 25 The frame 13 may be of wood, such as beech, which does not absorb odors. Other material may, of course, be used.

As shown in Fig. 3, an open front metal compartment 18, generally referred to as a liner, having outward flanges 19 along its forward edges, is secured around the door opening in the frame 13 by screws 20. The liner 18, which forms the storage compartment 11, may be coated on the inside with porcelain enamel, as well known, and 35 is provided in the rear with an opening, which may be referred to as a liner opening, surrounded by a wood frame 21 through which the cooling element 22 of a refrigerating apparatus may be inserted. To the liner opening frame 21 and the 40 front frame 13 are secured a plurality of insulating members 23 consisting of corrugated cardboard sheets faced with metal foil, in spaced relation to each other and parallel to the liner 18. The sheets 23 are provided with flanges 31 and 45 may be secured to the liner opening frame 21 and the front frame 13 by nails or other fastening means. It will be understood that the frames may be constructed of other material than wood, and other types of insulation may be employed.

50 The rear portion of the cabinet consists of upright corner posts 24 and 25 joined by a cross member 26, of steel or wood, at approximately the level of the front cross member 11. To the inside of the rear corner posts 24 and 25 are secured, for 55 example, by screws 27, the side edges 28 and 29

of a generally U-shaped metal plate 30 extending from the top of the posts 24 and 25 to approximately the level of the front cross member 11. The plate 30 forms the supporting structure for a refrigerating apparatus 31 the cooling element 22 of which is adapted to be disposed within the storage compartment 11.

The front section of the cabinet including the frame 13, the liner 18 and insulation members 23, and the rear section including the corner posts 24, 25, the plate 30 and the refrigerating apparatus 31, are telescoped together by inserting the cooling element 22 through the liner opening frame 21 into the storage compartment 11, forming a double cantilever arrangement whereby 15 both sections are mutually supporting. The plate 30 is provided with a block of insulation material 32 which is disposed within the liner opening frame 21. The liner opening is sealed on the 20 inside by a liner opening trim member 33.

The outer wall or casing 34 of the cabinet consists of an inverted U-shaped sheet of metal, which is given any desired finish, and which is placed over the rounded frame 13 and rear corner posts 24 and 25 and extends downwardly on 25 each side to the cross member 17. The casing 34 is secured by nails or screws to the wooden frame and corner posts. The top rear portion of the casing or cover 34 is cut out and provided with a downward flange 35 which is secured to the 30 plate 30 by means of metal screws. The cut-out is provided to permit good air circulation at the back of the cabinet for air cooling of the refrigerating apparatus 31. A flanged bottom plate 36, secured to the sides of the cover 34 along its 35 lower edges, to the front frame 13, and to the plate 30, serves to reinforce the structure.

Various changes may be made within the scope of my invention as indicated by the following claims.

40 What is claimed is:

1. Refrigerator including a cabinet having a front frame, a storage compartment secured to said frame, and rear corner posts, a refrigerating apparatus supported by said posts, and an outer 45 casing joining said frame and rear corner posts.

2. Refrigerator including a cabinet having a front frame, a storage compartment secured to said frame, insulation secured to said frame, and rear corner posts, a refrigerating apparatus supported by said posts, and an outer casing joining said frame and rear corner posts.

3. Refrigerator including a cabinet having a front frame, a storage compartment secured to said frame, insulation secured to said frame, and 55

rear corner posts, a refrigerating apparatus supported by said posts, and a unitary casing joining said frame and rear corner posts and forming the sides and top of said cabinet.

5 4. Refrigerator including a cabinet having a front frame, a storage compartment secured to said frame, insulation comprising spaced metal sheets and secured to said frame, and rear corner posts, a refrigerating apparatus supported 10 by said posts, and a unitary outer casing joining said frame and rear corner posts and forming the sides and top of said cabinet.

15 5. Refrigerator including a cabinet having a wooden front frame, a storage compartment screwed to said frame, insulation comprising corrugated cardboard sheets covered with metal foil nailed to said frame, and wooden rear corner posts, a refrigerating apparatus supported by said posts, an outer casing screwed or nailed 20 to said frame and rear corner posts, the upper portion of said frame forming the door opening and the lower portion of said frame and corner posts forming the legs of said cabinet.

25 6. Refrigerator including a front frame and a storage compartment secured thereto, a rear frame and refrigerating apparatus secured thereto, said parts being arranged to form a double cantilever, and an outer casing joining said frames.

30 7. Method of constructing a refrigerator comprising forming a front frame, storage compartment and insulation as a unit, forming a rear frame and refrigerating apparatus as a unit, bringing said units together in a double cantilever arrangement, and securing said frames together by a casing forming the sides and top of the refrigerator.

35 8. Method of constructing a refrigerator comprising forming a front frame, storage compartment and insulation as a unit, forming a rear frame and refrigerating apparatus as a unit, bringing said units together in a double cantilever arrangement, securing said frames together by a casing forming the sides and top of the refrigerator, and reinforcing the whole by securing a horizontal plate to said frames and casing immediately beneath said storage compartment.

40 9. Refrigerator including a cabinet having a front frame, a storage compartment secured to said frame, and rear corner posts, a metal plate secured to said posts, refrigerating apparatus

secured to said plate, and an outer casing joining said frame and rear corner posts.

45 10. Refrigerator including a cabinet having a front section and a rear section, said front section including a frame comprising upright members and cross members, a storage compartment secured to said frame having an opening in the rear wall thereof, a frame secured to said compartment around said opening, and insulation members secured to said opening frame and the 10 cabinet frame, said rear section comprising two corner posts, a cross member between said posts and a U-shaped plate secured to said posts, refrigerating apparatus mounted on said plate and having a cooling element adapted to be inserted 15 through the opening in said storage compartment and including means to insulate the opening, a unitary casing secured to said front frame and rear corner posts and forming the sides and top of the cabinet, and a flanged horizontal plate 20 secured to the inner sides of said outer wall at the lower edge thereof.

11. In a refrigerator, a first unit comprising a front upright frame supporting a rearwardly extending storage compartment, a second unit 25 comprising a rear upright frame supporting refrigeration apparatus including a forwardly projecting cooling element, said units being arranged to form a double cantilever structure with said cooling element telescoped into said 30 storage compartment, the latter being provided with a suitable opening for this purpose, and an outer casing secured to said frames and forming the sides and top of the refrigerator.

12. Refrigerator having a front section and a rear section, said front section including an upright frame forming a door opening and the front legs of the refrigerator, and a thermally insulated storage compartment mounted on said frame and having an opening in the rear to permit insertion of the cooling element, said rear section including an upright frame forming the rear legs of the refrigerator and refrigeration apparatus mounted on said frame and including a cooling element adapted to be inserted through 45 the opening in said storage compartment, said sections being arranged next each other with said cooling element projected into said storage compartment and forming a double cantilever structure, and an outer casing secured to said 50 frames and forming the sides and top of the refrigerator.

SIGURD MATTIAS BÄCKSTRÖM.
